UNITED STATES PATENT OFFICE.

CHARLES WHITE, OF BALTIMORE, MARYLAND.

GAS-ENGINE GOVERNOR.

1,071,193.

Specification of Letters Patent.

Patented Aug. 26, 1913.

Application filed November 27, 1912. Serial No. 733,919.

To all whom it may concern:

Be it known that I, CHARLES WHITE, a citizen of the United States, residing at Baltimore, Maryland, have invented certain new and useful Improvements in Gas-Engine Governors, of which the following is a specification.

My governor depends for its operation upon the inertia of a weight, the lag of which at the end of the stroke in one direction lifting the governor arm and preventing the opening of the gas supply valve, while at the other end of the stroke the weight is prevented from relative or swinging movement by the governor arm finding a bearing on the governor block. The weight is carried by a depending arm, and by adjusting this weight substantially horizontally or substantially at right angles to the depending arm, the speed of the engine may be changed.

The invention consists in the features and combination and arrangement of parts hereinafter described and particularly set forth 25 in the appended claims.

In the accompanying drawings Figure 1 is a side elevation of a gas engine cylinder with my improved governor in place to control the operation of the gas inlet valve; 30 Fig. 2 is an enlarged view of certain of the parts shown in Fig. 1; Fig. 3 is a cross sectional view substantially on the line 3-3 of Fig. 2; Fig. 4 is a plan view of the engine cylinder with my invention in place; 35 Fig. 5 is a detail sectional view of the gas valve box with the valve in place. Fig. 6 shows views of the weights. Fig. 7 is a detail view of the depending arm.

In these drawings, 1 is the engine cylinder, 2 the gas supply pipe leading to the gas valve, the box or casing of which is indicated at 3. Within the valve box the inlet valve 4 for the gas is seated, being pressed by a spring 5. Its stem 6 carries on its end a block 7, being held between a collar 8 and a collar 9 with a friction washer at 10, this construction permitting the block to be rotated on the valve stem so as to bring either the hit and miss tooth 11 uppermost, or to bring the graduated teeth 12 uppermost. These teeth are adapted to be engaged by a knife-edge member 13 carried by the arm 14 which is rigidly connected with a depending arm 15 carrying a weight 16. The arms 14 and 15 form a governor lever pivoted at 17 to a bracket 18 which is mounted on the rod 19 which reciprocates alongside of the engine cylinder, said rod being utilized for opening one of the valves of the engine through the lever 20, pivotally mounted at 21. The reciprocation of the rod 19 is derived through any suitable connection between it and the crank shaft of the engine, the sliding rod being guided in bearings 22. The arm 14 of the governor lever rests upon the block 7, finding a firm bearing thereon, which limits the movement of the lever and weight in one direction. I prefer to make the block 7 with upper and lower channels or grooves 23 adapted in 70 width and depth to receive the arm 14 of the governor lever, so that one will be sustained by the other, the arm 14, by resting in the groove, holding the block 7 against displacement or rotation on the valve stem, 75 and the parts being kept in line by this construction. The knife-edge member is seated in a notch or recess 24 in the upper side of the lever arm 14, and it is held in this recess by a screw 25. It projects, as 80 shown in Fig. 3, beyond the arm 14 at each side so as to engage the teeth on the block 7, which are formed therein at each side of the grooves 23. The governing action is due to the inertia of the weight 16. Supposing the rod 19 with the governor is on a movement to the right of Fig. 1, the inertia of the weight at the moment that the action of the parts reverses and moves toward the left will keep the arm 14 pressed 85 downwardly upon its bearing surface on the block 7, and all pendulum action of the weight under these conditions will be prevented. At the end of the leftward movement, when reversal takes place, if the speed 90 is normal the arm 14 will remain down in engagement with the block 7, and the knife-edge member will engage the tooth on the block, and thus on the stroke to the right the gas valve will again be operated to supply 95 the gas to the engine. If, however, the engine has attained a greater speed than that for which the governor is set, the inertia of the weight at the moment of reversing the stroke will cause the arm 15 to move 100 leftward, lifting the arm 14 and thus causing the knife-edge member to miss the tooth 11 (if the block is adjusted as illustrated), and allowing the gas valve to remain closed 105 during the movement of the governor to 110

ward the right, and reduce the speed of the engine. If the block 7 is turned about the valve stem to bring its series of teeth 12 uppermost, the engine will work on the graduated charge principle, the knife edge 5 13 engaging either one or the other of the series of teeth (which are at different elevations), and opening the gas supply valve at each movement of the rod 19 and governor to the right, the degree of opening varying, 10 however, in accordance with the demands of a constantly maintained uniform speed, such, for instance, where the engine is under a constant load as in running a generator for an incandescent circuit.

15 It will be noticed that the governor weight has no swinging movement at the end of the stroke to the right, the arm 14, as before stated, preventing this by finding a bearing 20 on the block 7. My governor is distinguished in this respect from pendulum governors in which a swinging movement takes place on the reversal of the stroke in either direction, giving rise to inaccuracies in the 25 governing action.

20 In order to secure the effect above described of preventing a pendulum like motion of the governor lever in one direction from its normal position it will be understood that the horizontal stroke of the end 30 of the horizontal arm 14 of the governor lever is such that in both its engaged and disengaged positions the governor lever will be supported against movement in one direction, this being due to the horizontal arm 35 resting on the block 7, which block in effect is a portion of the valve stem. In the form shown the weight will not at any time swing to the right beyond the position indicated. 40 In action the knife edge of the governor lever will jump over the tooth on the valve stem when the speed rises and it will then fall upon the block 7 and will be supported thereby to prevent the swinging of the 45 governor lever and weight. Supported in this position the end of the governor lever will be ready to slide back into position to engage the tooth of the block 7 when the stroke reverses.

50 The weight is adjustably mounted on the depending arm 15 of the governor lever. The weight has an opening 24' extending through it vertically which receives the depending arm 15 of the governor lever, and 55 it has also an opening 25' extending horizontally or lengthwise of the weight which receives an adjusting screw 26 having a finger piece 26' at one end and a boss or collar 27 at the other end. The lower end of the arm 60 15 is tapped to receive the screw, and by turning the screw rod the weight will be adjusted horizontally in relation to the governor arm, so that the preponderance of weight will lie either to one side or the other 65 of the axis or center line of the said arm,

the weight being elongated horizontally. No springs of any character are employed. The adjustment of the weight will cause the arm 14 to bear down on the block 7 more or less heavily, and the arm will be rendered 70 more or less sensitive to lifting when the reversal of the stroke takes place.

The arms 14 and 15 are connected together to move as one. The depending arm 15, as shown in Fig. 7, is split at its upper 75 end and is clamped to the pivot pin 17, to which also the arm 14 is fixed, as shown in Figs. 2 and 4.

What I claim as my invention is:

1. In an engine governor the combination 80 of a pivoted governor lever having a downwardly extending arm with a weight suspended thereon and a horizontally extending arm rigidly connected to the weighted arm and having detachable engagement with 85 the valve stem and means for bodily reciprocating the governor lever horizontally, the end of the said rigidly connected horizontal arm bearing upon a portion of the valve stem in both its engaged and disengaged 90 positions and thereby preventing the weighted arm from swinging in one direction from normal position.

2. In an engine governor the combination 95 of a pivoted governor lever having a downwardly extending arm with a weight suspended thereon and a horizontally extending arm rigidly connected to the weighted arm and having detachable engagement with the valve stem and means for bodily reciprocating the governor lever horizontally, the end of the rigidly connected horizontal arm being supported by a portion of the valve stem in both its engaged and disengaged 100 positions and preventing the weighted arm 105 from swinging in one direction from normal position, the said weight being adjustable across said depending arm and from one side thereof to the other and substantially parallel with the direction of bodily reciprocation of the governor lever, substantially 110 as described.

3. In combination in an engine governor, a lever pivotally mounted and having a horizontal arm detachably engaging the gas 115 valve stem, and a vertical arm with a weight lying partly on each side thereof and adjustable across said arm from one side to the other, and a screw rod carried by and turnable in the weight, said rod, when 120 turned, moving through the lower end of the vertical arm and carrying the weight with it, substantially as described.

4. In combination in a gas engine governor, a block on the valve stem having a 125 hit and miss tooth on one side and a series of graduated teeth on the other, and a governor arm to engage any of said teeth, said block being adjustable to bring either the hit and miss tooth or the series of graduated 130

teeth into position to be engaged by the arm, substantially as described.

5. In combination in a gas engine governor, a block swiveled on the valve stem adjustable by turning the same on said stem while remaining in connection therewith, said block having a hit and miss tooth on one side and graduated teeth on the other side, and a governor arm to engage said 10 teeth according to the adjustment of the block, with means for operating the said arm, substantially as described.

6. In combination with the valve stem, a block having a groove in its face, with 15 teeth above and on each side of the groove, and a governor arm fitted to the said groove and having a knife edge projecting to engage the teeth, with means for lifting the

arm from or holding it down in said groove, substantially as described.

7. In combination a governor block grooved on its upper and lower faces, and having a hit and miss tooth on one face and graduated teeth on the other face, a governor arm fitted to said grooves with means 20 for operating the governor arm, said block being swiveled on the valve stem to bring either face to coact with the governor arm, substantially as described.

In testimony whereof, I affix my signature in presence of two witnesses.

CHARLES WHITE.
